UNITED STATES PATENT OFFICE.

JOHN S. FINCH, OF BRIDGEPORT, CONNECTICUT, ASSIGNOR TO THE SINGER MANUFACTURING COMPANY, A CORPORATION OF NEW JERSEY.

LOOP-TAKER FOR SEWING-MACHINES.

1,048,672.

Specification of Letters Patent.

Patented Dec. 31, 1912.

Application filed March 22, 1912. Serial No. 685,591.

To all whom it may concern:

Be it known that I, JOHN S. FINCH, a citizen of the United States, residing at Bridgeport, in the county of Fairfield and State of Connecticut, have invented certain new and useful Improvements in Loop-Takers for Sewing-Machines, of which the following is a specification, reference being had therein to the accompanying drawings.

5 This invention has for its object to improve that class of sewing machine loop-takers which engage a loop of needle thread and, without passing through it, cast said loop about a cop or bobbin of under thread held in a non-rotating bobbin-case mounted in an annular groove in the inner wall of the flange forming the cast-off portion of the loop-taker, substantially as is represented by U. S. patent to W. F. Dial, No. 20 480,181, dated August 2, 1892, and as machines of this type are well understood by those versed in the art, the present description will be confined, in so far as is possible, to the new features in construction.

25 In the early constructions of loop-takers of the character referred to above, the extension leading from the loop-taker throat to the cast-off is convexed, between the base of the loop-seizing point and the periphery of the flange, in the direction of its rotation; and as is well understood, when the loop-seizing point has entered the thread loop a sufficient distance to place the latter in contact with the loop-taker throat, the further 30 rotation of the loop-taker draws from the supply, through the needle eye, sufficient thread to permit the bobbin-case to pass through the loop, the thread being drawn over the convex portion, which offers a substantial resistance to the enlargement of the loop and the casting of the latter about the bobbin-case. When employing a slack twisted thread, as is common to mercerized sewing cottons, such resistance demands a 35 substantial decrease in the speed of the machine from what would be practical in connection with the use of smooth, well twisted, sewing thread, and even when the thread is of the most favorable twist and finish, such frictional engagement is detrimental to 40 quality and quantity of product, if the machine is operated at a comparatively high speed.

45 To facilitate the relative action of loop-taker and needle thread is the object of the

present invention, and to this end the throat extension is so shaped as to permit the thread to lie in a straight line, thus eliminating the binding or frictional condition incident to its drawing over the convex surface 60 of said extension.

50 In the accompanying drawings illustrating the invention, in the several figures of which like parts are similarly designated, Figure 1 is a view, in elevation, of a loop-taker equipped with the present invention; Fig. 2 is a view in section on the line A—B, Fig. 1; Fig. 3 is an edge view of the loop-taker shown in Fig. 1 and Fig. 4 is a plan view of the base portion of one form of 70 commercial bobbin-case adapted for use in connection with the present loop-taker.

75 Referring to the figures, the loop-taker comprises the base or back wall 1 formed integral with it a flange 2 terminating at one end in a loop-seizing point 3 and at its opposite end in a heel 4, said flange being partially cut away for a portion of its length to accommodate the mounting of the adjustable gib 5. At the base of the 80 flange 2 is formed a guideway 6 for the reception of the guide flange 7 of the bobbin-case base 8, the adjustable gib 5 making it convenient to remove or replace the base 8, if desired, said gib being secured in operative relationship with said base by suitable screws (not shown) passing through openings, as 9, formed in said flange, and threaded into openings, as 10, formed in said gib.

85 11 represents a bracket or lug extending 90 out from the bobbin-case base 8 and which in practice contacts with a stationary lug (not shown) to hold said base against accidental rotation, and 12 is a bobbin-case base stud on which is mounted the commonly employed bobbin-case cap (not shown), between which and said base is mounted to rotate the commonly employed under thread bobbin or cop (not shown).

95 13 represents the loop-taker throat, 14 the throat extension, 15 the needle thread cast-off and 16 an inclined edge formed by the intersection of said extension and cast-off, the inner edge of said inclined edge and the lower edge of said extension intersecting and terminating at the inner edge of said cast-off.

100 17 represents a thread-loop guard formed integral with the loop-taker flange and acting to prevent the inner half of the thread 110

116

loop 18 from passing behind the flange; and while the providing of such guard comprises a preferred form of construction, it is to be understood that the invention is not limited in this respect, as it is practical to substitute the commonly employed loop-taker washer, such, for instance, as is shown at the back of the loop-taker in full-line Figs. 7 and 8 and in central cross-section, 10 Figs. 5 and 9, of Patent No. 480,181 referred to above.

In the operation of the loop-taker, as the needle thread passes in the direction of its length about the throat, the rotation of 15 the loop-taker causes the thread to ride the incline 16 its entire length (see Fig. 1), the throat acting as a pivot for the thread, and the incline acting to hold that portion of the thread leading from said throat to 20 said incline in a straight line, as will be readily understood.

The throat extension 14 and integrally formed loop guard 17 constitute the constructive features important to the present 25 invention, but as such features do not materially change the mode of operation for forming the stitch illustrated and described in the above mentioned patent, further reference to such operation is deemed unnecessary.

Claims:—

1. In a loop-taker for sewing machines for engaging a loop of needle thread and

without passing therethrough casting it about the under thread, the combination of 35 a loop-seizing point, a needle thread cast-off, a throat, a throat extension, and an inclined edge formed at the intersection of said cast-off and throat extension, said inclined edge acting to hold in a straight line 40 that portion of the needle thread loop leading from said inclined edge to said throat as said loop is carried by the rotation of the loop-taker in the direction of the axis of the latter.

45

2. In a loop-taker for sewing machines for engaging a loop of needle thread and without passing therethrough casting it about the under thread, the combination of 50 a loop-seizing point, a thread loop guard, a needle thread cast-off, a throat, a throat extension, and an inclined edge formed at the intersection of said cast-off and throat extension, said inclined edge acting to hold in a straight line that portion of the needle 55 thread loop leading from said inclined edge to said throat as said loop is carried by the rotation of the loop-taker in the direction of the axis of the latter.

In testimony whereof, I have signed my 60 name to this specification, in the presence of two subscribing witnesses.

JOHN S. FINCH.

Witnesses:

T. W. CUTTING,
ABBIE M. DONIHEE.
